US0D1100890S

(12) **United States Design Patent** (10) Patent No.: **US D1,100,890 S**
(45) Date of Patent: ** Nov. 4, 2025

(54) **CASE FOR MOBILE ELECTRONIC DEVICE**

(71) Applicant: **Samsung Electronics Co., Ltd.**, Suwon-si (KR)

(72) Inventors: **Miri Lee**, Suwon-si (KR); **Namsu Kim**, Suwon-si (KR); **Kihwan Kwon**, Suwon-si (KR); **Duyeong Choi**, Suwon-si (KR); **Dahyun Lee**, Suwon-si (KR); **Jieun Myung**, Suwon-si (KR); **Jiyun Lim**, Suwon-si (KR); **Sungwook Lee**, Suwon-si (KR)

(73) Assignee: **SAMSUNG ELECTRONICS CO., LTD.**, Suwon-si (KR)

(**) Term: **15 Years**

(21) Appl. No.: **29/905,153**

(22) Filed: **Oct. 17, 2023**

(30) **Foreign Application Priority Data**

Apr. 19, 2023 (KR) 30-2023-0015109

(51) LOC (15) Cl. **03-01**

CLAIM

The ornamental design for a case for mobile electronic device, as shown and described.

DESCRIPTION

FIG. 1 is a bottom front perspective view of a case for mobile electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top rear perspective view thereof; and,

FIG. 9 is a bottom front perspective view thereof, showing the case for mobile electronic device in an alternate position. The dashed broken lines in the figures depict portions of the case for mobile electronic device that form no part of the claimed design.
